UNITED STATES PATENT OFFICE.

RUFUS A. FREEMAN, OF FLUSHING, NEW YORK, ASSIGNOR TO THE AUTOPRESS COMPANY, A CORPORATION OF NEW YORK.

SHEET-SEPARATOR.

1,972,936.

Specification of Letters Patent. Patented Sept. 9, 1913.

Application filed October 1, 1907. Serial No. 385,388.

To all whom it may concern:

Be it known that I, RUFUS A. FREEMAN, a citizen of the United States, and a resident of Flushing, Queens county, State of New York, have invented certain new and useful Improvements in Sheet-Separators, of which the following is a specification.

The invention relates to sheet separators and in many of its aspects it relates more particularly to separators which operate upon a stack of sheets.

Objects of the invention are to provide a machine which will feed off the sheets from the stack one at a time with certainty and at high speed; to provide a separator in which the action is uniform and regular; to provide for repeated separating efforts upon each sheet through a relatively long period of time while maintaining a high rate of feeding off separated sheets; to provide separating devices having new and desirable features; to provide devices adapted to co-operate therewith to further the efficiency of the machine; and to provide for adjustment of the various parts, and for their relative adjustment and timing of their functions so as to secure the best results. These and other objects of the invention will in part be obvious and will in part more fully appear herein.

The accompanying drawings, referred to herein and forming a part hereof, illustrate one embodiment of the invention, the same serving in connection with the description herein to explain the principles of the invention.

Of the drawings: Figure 1 is a side elevation of a sheet-feeding machine built in part in accordance with the principles of this invention; Fig. 2 is a plan view thereof; Fig. 3 is a rear end elevation thereof; Figs. 4 and 5 are longitudinal sectional views, substantially on the line A—B of Fig. 2; Fig. 6 is a detail view of the carriage for the separating and feeding-off devices; and Fig. 7 is a central longitudinal sectional elevation of the sheet-feeding machine.

In the illustrated embodiment of the invention a stack of sheets 1 is placed upon a suitable support such as the table 2. Con-

veniently located with respect to the table and sheet stack are suitable sheet forwarding devices of any approved or convenient form. The said devices are shown herein as comprising a driven roll 3 carrying tapes 4 and also a series of drop rolls 5 located so as to coöperate with the roll 3 to take the sheet and start it upon the traveling tapes 4. The drop rolls 5 are raised and lowered in a well-known manner by any suitable mechanism, as for instance by arms 6 carried upon a shaft 7 mounted in the machine frame. There is shown fixed to the shaft 7 a lever arm 8 coöperating with a suitable cam 9, so as to give the necessary movement to the rolls 5.

It is contemplated by certain features of the invention to provide sheet-separating means constructed and arranged to have a highly efficient progressive separating action upon each sheet. The invention provides separating means constructed and arranged to exert a separating effort upon each sheet in the direction of its feeding off during a plurality of successive operations of the separating means. According to certain features of the invention, furthermore, the separating means are constructed and arranged to exert a separating action directly on each of a plurality of the sheets nearest the face of the stack in the direction of their feeding off at each operation of the separating means. In the embodiment of the invention illustrated herewith, and according to certain features of the invention, it is contemplated to have the separating means act in the manner indicated upon the sheet ends at the rear of the stack to exert a separating action in the direction of their feeding off. It is further contemplated by the invention in certain of its aspects to have the separating action exerted successively on the sheets toward the face of the stack from which the sheets are fed off. It will thus be understood that according to these particular features of the invention, the separating means may act upon the fanned-out ends of a plurality of the uppermost sheets in the stack. The invention, in certain of its aspects, contemplates also a further separating action.

applied to the face of the topmost sheet, which may, if desired, be continuous with the other action, so far as concerns many features of the invention.

5 The invention in certain of its aspects includes separating means which will exert a plurality of separating efforts of graduated pressure or intensity upon any particular sheet, or the end of a particular sheet, 10 during one operation of the separating means.

It will be understood that these various features of invention are conducive to a highly efficient separating action.

15 The prime object of separating sheets is, of course, to separate each single sheet successively from the stack with regularity and certainty, and it is also very desirable to do this at a high rate of speed. The progressive and graduated actions hereinbefore 20 specified provide an effective separating action, also a relatively long time for the separation of two sheets under the direct action of the separating means and for the 25 gradual destruction of the strong cohesion between successive sheets of the stack and notwithstanding this extended separating action on each particular sheet it is possible to keep up a high rate of feeding off the 30 sheets.

In the drawings herewith an embodiment 35 of the invention is shown comprising the features of invention above specified, together with other features of invention, as will appear elsewhere herein. In this embodiment separating means are provided having a combing action operating in accordance with the features of invention above specified, such a combing action being 40 contemplated by the invention in certain of its aspects. Certain other aspects of the invention include also the particular form and action of combing devices as will be more particularly specified elsewhere herein.

45 Referring to the drawings herewith, the combing device 10 comprises a series of rolls 11 arranged substantially in a plane and mounted in a suitable frame 12. The combing device 10 is further shown pivotally 50 mounted toward one end of the frame 12 upon an arm 13 which arm is in turn pivotally carried upon a bracket arm 14. Suitable devices are also provided for causing the combing device to exert pressure upon 55 the sheets and in the form thereof herewith illustrated a spring 15 is shown bearing upon the arm 13 and provided with an adjusting screw 16 for regulating the pressure.

Means are also provided in this embodiment for regulating the pressure of the various separating rolls 11 as they pass over the sheets, and the illustrated form of said means comprises a spring 17 mounted to exert pressure between the axis of the pivot 60 joining the arm 13 to the separating device

at one end of the frame 12 and a suitable lug 18 near the other end of the said frame. A screw 19 may be provided for regulating the pressure of the spring 17.

70 Means are provided, as hereinbefore indicated, for giving proper movement to the separating devices 10 and the form thereof illustrated in connection with the present embodiment comprises a carriage 20 slidably mounted in the frame of the machine, and 75 it is shown having trunnions 21 running in suitable guides 22 upon the said frame. The bracket arms 14 are fixedly carried upon a shaft 23 mounted in the carriage 20. A suitable reciprocating movement is communicated to the carriage 20 by any convenient means and in the illustrated embodiment a link 24 is shown pivotally connecting the carriage to a lever 25 which in turn is connected to an eccentric 26 mounted 80 upon a suitable shaft carried in the frame 85 of the machine.

90 In the illustrated embodiment the movement of the separating device toward and from the sheet stack so that it may return out of contact with the sheets is effected by the arm 13 swinging about its mounting on the bracket arm 14. The illustrated form of means for effecting this comprises a cam 95 27 which acts upon the arm 13 through the medium of a cam roll 28.

95 It is usually desirable to use a plurality of separating devices together upon the same machine and the present invention contemplates therefore means for adjusting a plurality of separating devices so as to bring them all into the same desired relation with respect to a stack of sheets of a given size which may be carried upon the table 2. It is generally found convenient to use two 100 separating devices acting upon opposite sides of the longitudinal center line of the sheets, and two devices so located are shown in connection with the present embodiment.

105 The cam roll 28 is mounted upon a rod passing through the arm 13 of each separating device. In the illustrated form the shaft 23 is shown carried slidably in the carriage 20. Near each end of the said shaft is a lug 29 tapped with a screw-thread which 110 receives a threaded rod 30. Mounted upon each of the threaded rods 30 is shown a miter gear 31 meshing with a similar gear upon a shaft 32. Upon turning the shaft 32 the two ends of the shaft 23 will move 115 in unison and the two or more separating devices will be carried in exactly the same relation backward or forward so as to come into proper relation with the particular sizes of sheets being fed. For convenience, the 120 shaft 32 is shown provided with a knurled hand piece 33.

125 Certain features of the invention contemplate also providing suitable feeding-out means for feeding the topmost sheet to the 130

sheet forwarding devices when it has been effectively separated from the other sheets. The form of such means illustrated in the accompanying drawings comprises a pusher finger or roll 34. The said roll is shown mounted upon an arm 35 pivotally carried by the carriage 20. Means are provided for placing an adjustable pressure upon the pusher roll or finger 34, the illustrated form thereof comprising a spring 36 acting upon the arm 35 and the tension thereof being regulated by a suitable adjusting screw 37 carried in a bracket 38. The feeding-off devices are shown herein as being two in number and also located on either side of the center of the machine, each of the arms 35 being pivoted on the corresponding bracket 38. The brackets 38 are adjustably mounted by set screws, as shown in Fig. 3, on the crossrod 39 of the carriage 20. Suitable means are provided for causing the said roll to have a forward movement in contact with the topmost sheet so as to feed it into the sheet forwarding devices, then to lift away from the face of the stack, to move backward free therefrom and to come into contact therewith preparatory for the next feeding-off movement. The form of such means shown in the accompanying drawings comprises an arm 40, forming an extension of the arm 35. The arm 40 of each feeding-off device is in connection with a rod carrying a cam roll 41. The said roll 41 is arranged to pass into and out of operative relation 25 with a cam 42 so as to lift the pusher roll 34 away from and to allow it to come into contact with the face of the sheet stack.

Means are provided, according to certain features of the invention, for regulating and harmonizing with respect to each other the action of the separating devices and the feeding-off devices. Certain features of the invention contemplate also providing means for varying the relations of the separating devices and the feeding-off devices and the time of the performance of their functions with respect to each other. Means for effecting both these functions are provided in the present embodiment, and the particular form thereof shown in the drawings will now be described.

Carried upon the carriage 20 is shown a bar 44, slidably mounted in a bearing 43. The end of the said bar works also in a slot in the bearing piece 45. The length of travel of the said bar may be limited by an adjustable stop 46 which is located so as to contact with shoulders upon the said bar outside of the slot in the piece 45. A suitable stop is provided at the other end of the bar 44 and the functions of all these parts will be more fully set forth herein-after. The cam member 27 is adjustably mounted upon the said sliding bar 44 by suitable means such as the binding screw 47.

The cam 42 is likewise mounted upon the said bar and may be adjustable, if desired. From the foregoing it will be obvious that in the construction described the springs 15 and 36 through their associated parts tend to hold the rod 44 so that within the limits of its travel it moves with the carriage 20 but when the bar engages the stops at either end of its travel said bar 44 ceases to move with the carriage 20 and then has relative movement with respect thereto and to the parts carried thereon. The effect of this will be more fully set forth in the statement of operation.

According to certain features of the invention, means are provided for regulating the effect of the separating means upon the sheets. The illustrated form of such regulating means comprises friction pads 48 shown bearing upon the surface of the sheet stack forward of the combing devices 10. The said pads 48 are carried upon pivotally-mounted arms 49 supported upon bracket arms carried by a shaft 50 slidably mounted in the machine frame. Springs 51 are utilized in this embodiment for exerting suitable pressure upon the friction pads 48 and adjusting screws 52 are likewise provided for regulating the tension of the springs 51. The pressure on the friction pads can thus be nicely adjusted so as to regulate the effect of a particular separating effort. By means of these and the various other adjustments described it is possible to regulate accurately the action of both sides of the machine. An adjusting device for positioning the friction pads for various sized sheets is provided and in the present embodiment the form thereof shown is substantially similar to the corresponding mechanism associated with the separating devices. A detailed description need not be given therefore and all the said parts are indicated generally by the reference numeral 53.

It is of course necessary to keep the top of the sheet stack in operative relation with respect to the various mechanisms. In the present embodiment this is effected by feeding up the table 2 as the sheet stack diminishes in height by reason of the sheets being fed off. Suitable means for effecting and also means for regulating this movement of the table are provided. The illustrated form of such means comprises supporting, guiding, and driving means for the table, detector means for gaging the level of the top of the sheet stack, and regulating devices controlled thereby for governing the action of the table-elevating mechanism. In the illustrated embodiment of such means there are shown legs 54 carrying the table 2 and moving in guides upon the frame of the machine. Attached to the table 2 is a sprocket chain 55 passing over sprocket wheels 56 at either end of its travel. Con-

nected to one of the sprocket wheels 56 by suitable gearing is shown a ratchet wheel 57. Located adjacent to the surface of the sheet stack is shown a roll 59 upon a bar 60 slidably mounted in a bracket 61 carried on the machine frame. Upon the end of the bar 60 is a collar 62 engaged by the forked end of an arm 63 carried by the shaft 64. Fixed to the shaft 64 is a bell-crank lever 65 to one end of which is pivoted the arm 66 having a pin-and-slot connection at its other end with the arm 8. The spring 67 co-acting with the shaft 64 tends to keep the pin and slot in the relation shown in Fig. 1 of the drawings. Connected to the other end of the bell-crank lever 65 is a rod 68 which is also connected to a pivotally-mounted pawl trip 69. The pawl 58 is mounted upon a sliding rod 70. The said rod 70 acting under the influence of the spring 71 would tend to move into engagement with a suitable cam 72. It is restrained therefrom, however, by reason of the pawl trip 69 being normally in position in rear of the lug 73 upon the pawl 58. As the sheets are fed off, however, the bell-crank lever 65 varies its path of travel, which it is permitted to do by reason of the pin-and-slot connection between the link 66 and the arm 8. As the pile of sheets decreases in height the point is reached when the throw of the bell-crank lever 65 lifts the pawl trip 69 from behind the stop 73 and the rod 70 is moved back under the influence of the spring 71 so that the pawl 58 will take a tooth upon the ratchet wheel 57 and the action of the cam 72 will then feed up the table. The elevation of the face of the sheet stack will again cause the trip 69 to pass behind the stop 73 and stop the elevating action until the face of the sheet stack has again sunk so as to cause a repetition of the action just described, when the drop roller is operated to remove the top sheet fed off the pile, the link 66 operates to raise the roller 59 off the sheet.

Means are contemplated by the invention for stopping the separating and feeding action. In the illustrated embodiment, means for stopping the said action by hand are provided including a pivoted stop 77 which may be thrown down, as shown in Fig. 7, so as to engage the bar 44 when in its rearmost position, and to prevent its being carried forward during the movement of the carriage 20. The stop may be thrown back into inoperative position, as shown in Fig. 4. Means are also provided for stopping the separating and feeding actions, should more than one be fed off the pile at one operation of the separating devices. As shown, the pawl 74 is connected with a detector device 75. The said pawl is adapted to engage with a series of ratchet teeth 76 carried upon the bar 44 so as to stop or limit the action of

the said bar under certain conditions. These devices constitute a part of the subject-matter of another application for patent filed by me contemporaneously herewith and need not be described in detail herein.

The operation of the herein-described mechanism is substantially as follows: A stack of sheets is loaded upon the table 2 which is properly adjusted as to height. The driving mechanism is started and through the eccentric 26 and lever 25 and the connected parts the carriage 20 is reciprocated backward and forward. The carriage 20 may be regarded as starting from its rearmost position. As has been hereinbefore explained, the bar 44 through the action of the springs 15 and 36 will be carried forward therewith. At this time the rolls 28 and 41 bear upon the bar 44 and not upon respective cams. The combing devices 10 act upon the sheets which are fanned-out in the manner shown in Figs. 4 and 5 of the drawings. It will thus be seen that each of the combing rolls 11 pass successively over the ends of the successive sheets near the top of the stack and that successive rolls also act upon a particular sheet. It will be seen also that by the movement of the parts and the action of the springs 15 and 17 the pressure exerted by successive rolls increases. Thus the separating effort is graduated into a succession of smaller efforts which vary in intensity thus producing a most excellent separating action. The path of travel of the separating device may be such that it also moves over the top surface of the top sheet during a portion of the separating action, as shown in Fig. 4. As the carriage 20 continues to move, the bar 44 comes in contact with the front stop and thereupon the roll 28 moves along the surface of the bar, riding upon the cam 27 and the arm 13 is thereby swung backwardly against the action of the spring 15 lifting the separating device 10 from the face of the sheet stack. The pusher rolls 34 in contact with the top sheet have also moved forward with the carriage, as shown in Fig. 4, and finally push the top sheet into the reach of the delivery device. The friction pads serve to regulate the combing operation and also to prevent a single sheet from being removed from the pile with the top sheet by the pusher rollers 34. The drop rolls 5 then bring the sheet into contact with the driven roll 3 and the top sheet is carried away by the travel tape 4. When the bar 44 has stopped, as previously described, the roll 41 rides upon the cam 42, and the pusher roll 34 is lifted out of contact with the sheet as it is fed away. The backward movement of the carriage 20 begins through the action of the eccentric 26 and lever 25, the bar 44 being carried backward by reason of the pressure of springs 15 and 36, as hereinbefore

explained. It will be noted that the cam rolls 28 and 41 are now riding upon their cams and during the backward movement the separating devices 10 and the pusher roll 34 are out of contact with the surface of the stack, as shown in Fig. 5 of the drawings. As the parts travel backward the bar 44 contacts with the rear stop 46 and the cam rolls 28 and 41 now ride off their cams and the separating devices 10 and the pusher rolls 34 again come into contact with the top of the sheet stack. It will be understood further that the action of the separating devices 10 and of the pusher rolls 34 may be varied by varying the position of the stops which limit the travel of the bar 44 and also that the relative position, travel, and the functional timing of the separating devices and the feeding-off devices may be regulated by varying the relative position of the cams 27 and 42. Other means of regulating these devices have been fully described in connection with their respective construction. The operation of the remaining parts will be clearly understood from the description and from the drawings and need not be set forth in detail.

From all the foregoing it will be understood that a sheet-feeding machine has been provided which realizes the objects of invention and the advantages herein set forth, together with other objects and advantages.

The invention, in its broader aspects, is not limited to the particular construction shown, nor to any particular constructions by which it has been or may be carried into effect, as many changes may be made in the construction without departing from the main principles of the invention and without sacrificing its chief advantages.

What I do claim as my invention and desire to secure by Letters Patent, is:

1. A sheet-feeding machine including in combination, means for supporting a sheet stack, separating means constructed and arranged to exert intermittently a series of progressive separating actions directly upon each of a plurality of sheets during each of a plurality of successive operations of the said means, and means for operating said separating means.

2. A sheet-feeding machine including in combination, means for supporting a sheet stack, separating means constructed and arranged to exert intermittently a series of separating actions directly on each of a plurality of the sheets nearest the top of the stack during each of a plurality of successive operations of the said means, said separating actions being exerted in the direction of feeding off, and means for operating said separating means.

3. A sheet-feeding machine including in combination, means for supporting a sheet stack, separating means constructed and ar-

ranged to exert a series of progressive separating actions of varying intensity directly upon each of a plurality of sheets during each of a plurality of successive operations of the said means, and means for operating said separating means.

4. A sheet-feeding machine including in combination, means for supporting a sheet stack, separating means constructed and arranged to exert intermittently a series of progressive separating actions directly upon the rear ends of each of a plurality of sheets during each of a plurality of successive operations of the said means, said actions being exerted in the direction of feeding off, and means for operating the said separating means.

5. A sheet-feeding machine including in combination, means for supporting a sheet stack, separating means comprising a reciprocating combing device constructed and arranged to exert during each reciprocation a series of separating actions directly on each of a plurality of sheets nearest the top of the stack in the direction of feeding off, means for rendering said device inoperative when moving in the opposite direction, and means for reciprocating the said combing device.

6. A sheet-feeding machine including in combination, means for supporting a sheet stack, separating means comprising a combing device constructed and arranged to exert a series of progressive separating actions of varying intensity simultaneously directly upon each of at least three successive sheets during each of a plurality of successive operations of the said means, and means for operating said separating means.

7. A sheet-feeding machine including in combination, means for supporting a sheet stack, separating means comprising a reciprocating combing device constructed and arranged to exert during each reciprocation a series of separating actions of varying intensity directly upon each of a plurality of sheets near the top of the stack, means for reciprocating said device, means for rendering said device operative during its motion in one direction, and means for rendering said device inoperative during its motion in the opposite direction.

8. A sheet-feeding machine including in combination, means for supporting a sheet stack, separating means comprising a reciprocating feeding off device, a reciprocating combing device constructed and arranged to exert a progressive separating action directly upon the rear ends of a plurality of sheets near the top of the stack during each operation of the separating means, means for reciprocating said devices, means for rendering said devices operative during their movement in one direction, and means for rendering said devices inoperative dur-

ing their movement in the opposite direction.

9. A sheet-feeding machine including in combination, means for supporting a sheet stack, separating means comprising a reciprocating feeding off device, a reciprocating combing device constructed and arranged to exert a series of progressive separating actions directly upon a plurality of sheets during each of a plurality of successive operations, means for reciprocating said devices, means for rendering said devices operative during their movement in one direction, and means for rendering said devices inoperative during their movement in the opposite direction.

10. A sheet-feeding machine including in combination, means for supporting a sheet stack, separating means comprising a reciprocating feeding off device, a reciprocating combing device constructed and arranged to exert during each reciprocation a series of separating actions of varying intensity directly upon each of a plurality of sheets near the top of the stack, means for reciprocating said devices, means for rendering said devices operative when moving in one direction, and means for rendering said devices inoperative when moving in the opposite direction.

11. A sheet-feeding machine including in combination, means for supporting a sheet stack, separating means comprising a reciprocating combing device including a series of combing rollers, means for reciprocating said device, means for causing the respective rollers of the series to successively exert a graduated pressure upon the stack during the movement of the device in one direction, and means for relieving said device from pressure when moving in the opposite direction.

12. A sheet-feeding machine including in combination, a support for a sheet stack, a reciprocating combing device carrying a plurality of freely rotatable combing rollers arranged substantially in a plane, means for reciprocating said device, and means for varying the pressure exerted upon the sheets by the different rollers.

13. A sheet-feeding machine including in combination, a support for a sheet stack, a reciprocating combing device carrying a plurality of freely rotatable combing rollers arranged substantially in a plane, means for reciprocating said device, means for causing the respective rollers of the series to exert different pressures upon the stack during the movement of the device in one direction, and means for removing the pressure of the rollers during the movement of the device in the opposite direction.

14. A sheet-feeding machine including in combination, a support for a sheet stack,

a reciprocating combing device carrying a plurality of combing rollers, an automatic means for causing the successive rollers to exert a gradually increasing pressure upon the stack during the movement of the device in one direction, and means for removing the pressure of the rollers during the movement of the device in the other direction.

15. A sheet-feeding machine including in combination, means for supporting a sheet stack, separating means comprising a reciprocating feeding off device operating on the forward part of the stack and a reciprocating combing device including a series of combing rollers arranged to operate on the rear of the stack, means for reciprocating said devices, means for rendering them operative during their motion in one direction, and means for rendering them inoperative during their motion in the opposite direction.

16. A sheet-feeding machine including in combination, means for supporting a sheet stack, separating means comprising a reciprocating feeding off device, a reciprocating combing device including a series of combing rollers, means for reciprocating said devices, means for causing the reciprocating combing rollers of the series to successively exert a graduated pressure upon the stack during the movement of the devices in one direction, and means for rendering both devices inoperative during their movement in the opposite direction.

17. A sheet-feeding machine including in combination, a support for a sheet stack, separating means comprising a reciprocating feeding off device operating on the forward part of the stack, a reciprocating combing device having a plurality of combing rollers arranged to operate upon the rearward part of the stack, means for reciprocating said devices in unison, means for causing said devices to operate upon the stack with varying pressures during the forward stroke, and means for rendering said devices inoperative during the return stroke.

18. A sheet-feeding machine including in combination, a support for a sheet stack, separating means comprising a reciprocating feeding off device operating on the forward part of the stack, a reciprocating combing device operating on the rearward part of the stack, means for reciprocating said devices, means for causing said devices to operate with predetermined pressures upon the stack during the forward stroke, and means including a member reciprocating with said devices for rendering the same inoperative during the rearward stroke.

19. A sheet-feeding machine including in combination, a support for a sheet stack, separating means comprising a reciprocating

ing feeding off device operating on the forward part of the stack, a reciprocating combing device operating on the rearward part of the stack, means for reciprocating said devices, means for causing said devices to operate with predetermined pressures upon the stack during the forward stroke, means including a member reciprocating with said devices for rendering the same 10 inoperative during the rearward stroke, and means operating on said reciprocating member for rendering the separating means inoperative.

20. A sheet-feeding machine including in combination, a support for a sheet stack, separating means comprising a plurality of feeding off devices arranged to operate with independently adjustable yielding pressure on the forward part of the stack and a plurality 15 of combing devices arranged to operate with independently adjustable yielding pressure on the rearward part of the stack, means for reciprocating said devices in unison, means for rendering said devices operative during the forward stroke, and means for rendering said devices inoperative 25 during the rearward stroke.

21. A sheet-feeding machine including in combination, a support for a sheet stack, separating means comprising a plurality of feeding off devices arranged to operate on the forward part of the stack and a plurality of combing devices arranged to operate on the rearward part of the stack, means for reciprocating said devices in unison, means for causing said devices to bear upon the stack with predetermined pressures during the forward stroke, and means including a member reciprocating with said devices for 35 rendering the same inoperative during the rearward stroke.

22. A sheet-feeding machine including in combination, a support for a sheet stack, separating means comprising a plurality of feeding off devices arranged to operate on the forward part of the stack and a plurality of combing devices arranged to operate on the rearward part of the stack, means for reciprocating said devices in unison, means 45 for causing said devices to bear upon the stack with predetermined pressures during the forward stroke, means including a member reciprocating with said devices for rendering the same inoperative during the rearward stroke, and means operating on said member for rendering said separating means 55 inoperative.

23. A combing device for a sheet-feeding machine comprising a supporting member, a series 60 of freely rotatable combing rollers carried by said member and arranged substantially in a plane, an arm pivoted to said member, and means for reciprocating said arm.

65 24. A combing device for a sheet-feeding

machine comprising a supporting member, a series of freely rotatable combing rollers carried by said member and arranged substantially in a plane, an arm pivoted to said member, means for reciprocating said arm, 70 means for exerting pressure upon said combing rollers during the movement of said arm in one direction, and means for removing said pressure during their movement in the opposite direction.

25. A combing device for a sheet-feeding machine comprising a supporting member, a series of combing rollers carried by said member and arranged substantially in a plane, an arm pivoted to said member, means for exerting a predetermined pressure on said arm, and means for exerting a predetermined pressure between said member and the said arm to which it is pivoted.

26. A combing device for a sheet-feeding machine comprising a supporting member, a series of combing rollers carried by said member and arranged substantially in a plane, an arm pivoted to said member, means for exerting a predetermined pressure on 80 said arm, and means for exerting a predetermined pressure upon the said member tending to give the latter an angular motion about its pivot whereby the combing rollers are caused to bear upon the sheets with different pressures.

27. A sheet separating mechanism including in combination, a support for a sheet stack, a feeding off device arranged to operate by frictional contact with the top of 100 the stack, a combing device arranged to comb the sheets in the direction of the feeding off movement thereof by direct contact simultaneously upon a plurality of successive sheets, and sheet holding means arranged to engage 105 the rearward end of the second sheet while the top sheet is being removed by the feeding off device.

28. A sheet-separating mechanism including in combination, a support for a sheet 110 stack, a plurality of feeding-off devices arranged to operate with independently adjustable yielding pressure upon the forward part of the stack, a plurality of combing devices arranged to operate with independently 115 adjustable yielding pressure upon the rearward part of the stack, and a plurality of sheet holding devices arranged to engage the rearward end of the second sheet while the top sheet is being removed by the feeding-off devices.

29. A sheet separating mechanism including in combination, a support for a sheet stack, a feeding off device arranged to operate by frictional contact with the top sheet 125 of the stack, means for varying the degree of such frictional contact, and combing devices arranged to comb the sheets in the direction of the feeding off movement thereof, means for varying the degree of the comb-

ing action, sheet holding means arranged to engage the rearward end of the second sheet while the top sheet is being removed by the feeding off device, and means for varying 5 the holding effect of such sheet holding means.

In testimony whereof, I have signed my

name to this specification, in the presence of two subscribing witnesses.

RUFUS A. FREEMAN.
